GARMENT HANGER

Filed April 27, 1925

2 Sheets-Sheet 2

WITNESS: Gerald Kennedy, Jr.

ATTORNEY

UNITED STATES PATENT OFFICE.

BRYANT SIMPSON, OF WASHINGTON, DISTRICT OF COLUMBIA.

GARMENT HANGER.

Application filed April 27, 1925. Serial No. 26,233.

To all whom it may concern:

Be it known that I, BRYANT SIMPSON, a citizen of the United States, residing at Washington, in the District of Columbia, have invented new and useful Improvements in Garment Hangers, of which the following is a specification.

My present invention has reference to a garment hanger.

10 My object is the provision, in a device for this purpose, of means for effectively supporting either a one or two piece garment in a manner whereby the garment will be sustained in its form when worn, so that 15 both the front, sides and rear of the garment may be effectively displayed.

A further object is the provision in a garment support, of means for holding the front and back of garment from contacting 20 engagement which not only permits of the garment assuming its form when arranged on the wearer but holds the parts constituting the same separated in a manner that will prevent the creasing or bulging thereof, an 25 especially desirable feature when the garment retains dampness after being pressed or cleaned, inasmuch as the air is permitted a free circulation to the interior as well as the exterior of the garment.

30 A still further object is the provision of a device for this purpose embodying a coat hanger having bowed members secured to the opposite faces thereof for contacting with the front or breast portion and the 35 back of a coat for holding these portions of the garment out of contact with each other, and in which there is adjustably suspended from the hanger a sectional ring for contacting engagement with the waist of the skirt portion of the garment for holding the same in open position, there being means on the ring for effectively supporting the skirt thereon.

A still further object is the provision in 45 a garment hanger, of a band suspended from a coat hanger for contacting with the waist of the skirt or trousers of a garment, the said ring being adjustably suspended from the hanger and being constructed of 50 two adjustably associated spring members connected together by telescopic and consequently adjustable means and whereby the sectional ring member may be adjusted to properly engage the waist bands of different size garments, there being means on the

ring for effectively gripping the garment to suspend the same therefrom.

A still further object is the provision in a garment hanger that includes a coat supporting member, of an adjustable ring or band suspended from the hanger at desired elevations to permit of the longitudinal or lateral movement of the band on its support, the said band comprising two flat slotted 60 spring members pivotally associated with a telescopic member to which the suspending means is attached, the said bands being bowed from their connection with the said telescopic member, adjustable with respect to each other, carrying means for clamping 65 a garment thereto and susceptible for swinging against each other on the said telescopic member and for gripping a garment for sustaining the same in flat condition, as when the device is employed for supporting the 70 trousers of a man's suit.

The improvement also resides in the novel features of construction and operative association of elements such as will be herein-after clearly set forth in the following description, illustrated by the accompanying drawings and pointed out with particularity 80 in the appended claims.

In the drawings:—

Figure 1 is a perspective view illustrating 85 a two part ladies' garment supported in accordance with this invention.

Figure 2 is a perspective view of the improvement.

Figure 3 is a similar view of the coat 90 hanger portion of the improvement.

Figure 4 is an edge view of the construction disclosed in Figure 3.

Figure 5 is a perspective view of the band portion of the improvement.

Figure 6 is a fragmentary perspective view to illustrate the manner in which the ends of the metal straps constituting the bands are disposed in lapping unison for association with one end of the telescopic 100 member, and the elements associated with the pivot for the band.

As disclosed by the drawings, I make use of a coat hanger 1 of the usual construction. The hanger 1 is centrally provided with a 105 suspending hook 2 on its outer edge and on its inner edge with an oppositely arranged hook 3. The purpose of the hook 3 will presently be apparent. On the angle arms of the hanger 1, adjacent to the ends there- 110

of, there are secured inner and outer eyes 4, respectively. To these eyes there are removably connected the eye ends 5 on the straight arms 6 of wire members 7 and 8, respectively. The arms 6, at a determined distance from their pivotal connection with the eyes 4 are bent upon themselves to provide loops 9 designed for engagement with hooks 10 on the opposite faces of the hanger 1. From the loops 9 the members 7 and 8 are bowed outwardly at a downward angle with respect to the hanger 1, as indicated by the numerals 11 and 12, respectively. The wire constituting the member 7 is of a less length than that of the member 8. Consequently the loop 12 is of a greater length than that of the loop 11. The loop 11 is designed for contacting engagement with the inner face of the back of the coat portion 20 of a garment, while the loop 12 contacts with the inner face of the front of the garment. In this manner it will be noted that the front and back of the garment are held spaced from each other so that air can freely circulate through the garment. This construction is especially desirable by tailors or garment cleaners, as it is necessary to dampen the garment in the cleaning and in the pressing thereof. Were the garment permitted to rest on the usual form of coat hangers, the front and back thereof would contact with each other and the dampened garment, especially the inner lining thereof, would have a tendency to crease or bulge as the moisture evaporates therefrom with the result that the effectiveness of the pressing operation of the garment is lost. In addition to preserving the shape of the garment the construction of my improvement permits of both the front and back of the said garment being clearly inspected by the owner or by a purchaser. The hanger as above described may be employed with equal efficiency on upper garments for either gentlemen or ladies.

The skirt portions of ladies' garments, when pressed and cleaned are also susceptible to wrinkling and loss of shape, unless air is permitted to circulate therethrough and also the ladies' skirts or lower garment, when suspended from an ordinary hanger will not be fully displayed, that is the garment must be taken by the hand of a perspective purchaser to inspect both the front and rear thereof. It is also the primary object of this invention to overcome these objections and therefore, I attach to the inner hook 3 a flexible element, such as a chain 13. Any of the links of this chain is designed for engagement by a hook 14 arranged for longitudinal sliding movement on a track 15, preferably formed of a U-shaped wire whose ends are secured to the upper face of a block 16. The block has a rectangular bore entering from one end

thereof and in this bore there is telescopically received a rod 17 formed on the end of a comparatively short block 18. The cross sectionally rectangular rod 17 has its under face provided with spaced transverse notches 19 and the block 16 has pivotally secured to its under face a metal member 20 having an offset tongue 21 for engagement with any one of the notches 19. The latch plate 20 is pivoted, as at 22, and the said plate is provided with an offset end forming the same with an operating handle 23. In this manner, the telescopically associated elements 16 and 18 may be longitudinally adjusted to lengthen or shorten the same. 80

The members 16 and 18 have extending from their outer ends the threaded studs 24. One of the studs 24 is designed to be passed through aligning openings in the lapping ends of comparatively thin spring straps 25 and 26, respectively. The straps 25 and 26, at suitable points from their pivoted ends, are formed with central longitudinally extending slots 27, respectively, which terminate at points close to their opposite and free ends. The straps 25 and 26 are rounded upon themselves so that the free ends of the said straps are disposed in lapping relation to receive through the slots 27 there-in the second pintle 24. Both pintles 24 pass through openings in flanged plates 28. The edge flanges of these plates are disposed over the edges of the straps or bands 26 and 27. The threaded pintles 24 have screwed thereon milled nuts 29 which bind the lapping ends of the straps or bands 25 and 26 against each other and against the ends of the telescopic members 16 and 18. By an arrangement as above described, it will be noted that the circumference of the band may be regulated to a nicety. Also incident to the telescopic association of the members 16 and 18, the connected ends of the bands may be spread to cause the said bands to assume an elliptical shape. By 110 this arrangement the bands may be made to properly engage with the waist band of a skirt or like lower garment for ladies' wear.

The plates 28 have preferably soldered or otherwise secured on the outer faces thereof, loops 30, and to the outer faces of these loops there are pivoted or otherwise secured the inner elements of spring jaw clamps 31. Slidably arranged on the sections 25 and 26 of the band there are loops 32 which carry on their outer faces spring jaw clamps 35. The clamps 31 and 33 are designed for gripping the waist band of the garment suspended from the device. 115

The sections 25 and 26 of the band may be swung to the dotted line position in Figure 2 of the drawings in which event the spring jaw clamps may be employed for engaging the waist band of a pair of trousers. When thus arranged it will be 130

noted that the device, when employed as a hanger for mens' garments will support thereon an extra pair of trousers, and it is thought that the foregoing description 5 when taken in connection with the drawings will fully set forth the simplicity of my improvement and the advantages there- 10 of to those skilled in the art to which such invention relates. The construction, of course, is necessarily susceptible to slight changes and modifications especially with respect to proportion, material employed, etc., as for instance, the bowed members 15 7 and 8 may be directly hinged to the hanger 1 and the member 7 may be shaped so that the same can be folded against the inner face of the said hanger without projecting therebeyond when the hanger is not in use. Therefore I am not to be restricted 20 to the precise details herein set forth and hold myself entitled to make such changes therefrom as fairly fall within the scope of what I claim.

Having described the invention, I 25 claim:—

1. A suit hanger having eyes on its opposite faces adjacent to the arms thereof, wire members having their ends pivotally secured to the eyes, said wire members being 30 looped and from thence bowed outwardly at opposite angles, hooks on the sides of the hanger for engaging with the bowed portions of the wire members, and one of said wire members being of a greater length 35 than the other.

2. A suit hanger having bowed members secured to the opposite sides thereof, a chain centrally depending from the hanger, a block comprising telescopic members, means for adjusting the members with 40 respect to each other, a track on the telescopic block, a hook slidable on the track for engaging one of the links of the chain and a split spring band removably and adjustably secured to the ends of the telescopic block and carrying garment engaging 45 clamps.

3. A suit hanger having bowed members secured to the opposite faces thereof, and extending at opposite downward angles 50 with respect thereto, a chain centrally depending from the hanger, a block comprising telescopic sections, means for holding one of the sections adjusted with respect to the other section, a substantially U- 55 shaped track on the block, a slideable hook thereon for engaging one of the links of the chain, a band comprising two spring sections, having their ends in lapping relation and one of said ends pivotally secured 60 to one end of the block, said bands from their said pivoted ends having elongated slots, a pivot at the second end of the block passing through the slots, flanged plates 65 engaged by both pivots, spring jaw clamps on the plates, and loop members on the bands carrying spring influenced jaws for the purpose set forth.

In testimony whereof I affix my signature.
BRYANT SIMPSON.
